UNITED STATES PATENT OFFICE.

HAROLD J. BELL, OF PHILADELPHIA, PENNSYLVANIA, ASSIGNOR TO THOMAS DEVLIN, LOUIS J. MCGRATH, WILLIAM K. BROWN, AND CATHARINE A. MCGRATH, EXECUTORS OF WILLIAM V. MCGRATH, DECEASED, OF SAME PLACE.

DESIGN FOR A RADIATOR.

SPECIFICATION forming part of Design No. 21,986, dated November 8, 1892.

Application filed June 15, 1892. Serial No. 436,867. Term of patent 14 years.

To all whom it may concern:

Be it known that I, HAROLD J. BELL, a citizen of the United States, residing in the city of Philadelphia, State of Pennsylvania, have 5 invented a certain new and original Design for Steam and Hot-Water Radiators, of which the following is a full, clear, and exact description, reference being had to the accompanying drawing, forming a part of this specification.

My invention relates to steam and hot-water radiators; and it consists of the design for the external ornamentation thereof, as herein-after described, and as shown in the accompanying drawing, which is a perspective view of a series of "loops" or pairs of radiator-pipes set up and connected together on supporting feet and constituting the complete radiator and of the design therefor. Each loop or pair 15 of pipes contains that part of the design which consists of a shell-like figure A at or near each top and bottom end of the pipe, and between the same a twisted cord B, on either side of which at intervals is arranged a series of stars 20 C, and these features constitute the leading and distinguishing characteristics of the de-

sign. The top and bottom ends are, however, further ornamented as follows, viz: Above the shell-like figure A, at the top of each pipe, is a rosette D and below the shell-like figure A, 30 at the bottom of each pipe, is a double cross-hatched surface E, and below that again at F a repetition in substance of the shell-like pattern, and the supporting-legs are also ornamented with the same figure F. 35

Having thus described my invention, I claim—

1. The design shown for radiator-pipes, consisting of the parts A B C, substantially as set forth. 40
2. The design shown for loops or pairs of radiator-pipes, consisting of the ornamental figures A B C D E F, arranged substantially as set forth.

In testimony whereof I have hereunto 45 affixed my signature this 10th day of June, A. D. 1892.

HAROLD J. BELL.
